W. R. BEARCE & R. J. JONES.
TOY FIREARM.
APPLICATION FILED SEPT. 15, 1915.

1,184,410.

Patented May 23, 1916.

UNITED STATES PATENT OFFICE.

WILSON R. BEARCE AND REES J. JONES, OF SAWTELLE, CALIFORNIA, ASSIGNEES OF
ONE-THIRD TO FRANCESCO HAMMOND, OF CASEY, ILLINOIS.

TOY FIREARM.

1,184,410.

Specification of Letters Patent.

Patented May 23, 1916.

Application filed September 15, 1915. Serial No. 50,837.

To all whom it may concern:

Be it known that we, WILSON R. BEARCE and REES J. JONES, citizens of the United States, residing at Sawtelle, in the county of 5 Los Angeles and State of California, have invented certain new and useful Improvements in Toy Firearms, of which the following is a specification.

This invention relates to the general subject of toys, and has special reference to a 10 moot firearm particularly adapted for juvenile amusement and play.

To this end the invention contemplates a novel and substantial device which closely 15 resembles a pistol or revolver in appearance, and which is adapted to eject a soft rubber ball. It will therefore be apparent that the invention proposes to provide an attractive and amusing toy that may be safely handled 20 without danger of injury or accident.

A further object of the invention is to provide a simple and reliable device involving but few inexpensive parts that may be 25 readily assembled and easily manipulated.

With the above and other objects in view 30 which will more readily appear as the nature of the invention is better understood, the same consists in the novel construction, combination and arrangement of parts hereinafter more fully described, illustrated and claimed.

A preferred and practical embodiment of the invention is illustrated in the accompanying drawings, in which—

Figure 1 is a side elevation of the improved toy forming the subject of the present invention. Fig. 2 is a longitudinal sectional view showing the plunger in set position in full lines and the ejecting position 40 when released by the trigger device in dotted lines. Fig. 3 is a view similar to Fig. 2 illustrating the position of parts when the plunger is being drawn into the set position shown in Fig. 2. Fig. 4 is a cross section on 45 the line 4—4 of Fig. 2.

Similar reference characters designate corresponding parts throughout the several figures of the drawings.

In carrying out the present invention any 50 material suitable for the purpose may be used. However, it is preferred to construct the toy of wood or a light metal which will not be cumbersome or unwieldy, thereby permitting the same to be easily handled.

55 In either case, in order to facilitate assem-

bling of the several parts, the barrel 1 is preferably made in two parts or halves *a* and *b* as shown in Fig. 4 which are held together by suitable pins or rivets *c*.

With particular reference to the construction of the barrel 1, it will be observed from the several figures of the drawings that the same is of the usual tubular formation having a cylindrical bore 2 of uniform diameter throughout, and which terminates at the muzzle end of the gun in an enlarged ball receiving recess 3. The breech end of the bore 2 is preferably closed as indicated at 4, except for a vertically disposed slot 5, thus constituting an abutment for the coil spring 6 of the plunger device P. This plunger device preferably includes a plunger head 7 of disk like form, and a bent wire stem 8 having a loop portion 9 at one end and its free ends 10 riveted to the plunger head 7. It will thus be apparent that the plunger device P is slidable in the bore 2 of the barrel, and that the head 7 thereof is thrust forward by the coil springs 6, while the stem 8 thereof may freely slide in the slot 5 at the breech end of the bore. The breech end of the barrel 1 is also provided with a trigger extension 11 having pivoted therein as at 12 an angular trigger piece 13. The forward end of the said trigger piece is pivotally connected as at 14 with a vertically slidable detent 15 located at the breech end of the bore 2 and having a flat T-head portion 16 which is adapted to engage with a notch 17 in the stem 8 of the plunger device P. For the purpose of maintaining the detent 15 in its normal position, the same is surrounded by a coil spring 18 having its upper end in supporting engagement with the underside of the T-head 16, and its lower end abutting against the shoulder 19 of the cylindrical spring housing 20.

The trigger extension 11 at the breech end of the barrel has hinged thereto as indicated at 21 a stock member S which includes a breech block 22 and a handle H. The said breech block 22 is provided with a suitable clearance recess 23 having at one end thereof a cross pin 24 which is adapted to engage with the loop end 9 of the wire stem 8 of the plunger device, to set the same, and slide in the slot of the stem after the plunger device has been drawn into set position. With further reference to the stock portion of the gun, it will be observed

100

105

110

that the same has formed in the top of the breech block portion thereof a locking depression 25 which is adapted to receive the hook portion 26 of a spring latch piece 27 rigidly secured to the barrel 2 as indicated at 28. Thus, when the stock is in its closed position with relation to the breech end of the barrel, it will be apparent that the same is rigidly held locked thereto, so that 10 there is no danger of the barrel and stock being separated during the normal use of the toy.

It is now thought it will be clear that the reciprocating plunger device P may be easily 15 manipulated to forcibly project the soft rubber ball B from the end of the barrel, to which it may be tied by a suitable length of elastic cord C. However, by way of setting forth the operation of the invention, it will 20 be observed that the ball B may be pushed within the recess 3 at the muzzle of the barrel, and then the barrel grasped in one hand and the stock in the other, and these parts moved relatively to each other on the hinge 25 21 so that the pin 24 in the breech block will engage the loop end 9 of the stem of the plunger device as shown in Fig. 3, to draw the said stem rearwardly and compress the spring 6. When the breech block has moved 30 back a sufficient distance, the T-head 16 of the detent 15 of the trigger device will snap into the notch 17 on the stem 8, and thus hold the plunger device in position to discharge the ball until pressure is applied to 35 the trigger piece 13. After the stock has been turned the limit of its movement to bring the head of the detent into the notch 17, the same may be closed or turned back to its normal position, and in this movement, 40 the loop end 9 of the stem 8 will slide back into the recess 23 of the breech block as clearly shown in Fig. 2. With the parts of the device as shown in this latter figure, pressure upon the trigger piece 13 will 45 cause the detent 15 to move downwardly, and thus release the stem 8 of the plunger device, and permit the plunger head 7 to jump forward under the action of the spring 6, and thus eject the ball B from the muzzle 50 end of the barrel.

From the foregoing description, it is thought that the many features and advantages of the present invention will be readily apparent to those familiar with the 55 art, and it will also be understood that changes in the form, proportion, and minor details of construction may be resorted to without departing from the spirit of the invention or scope of the appended claims.

60 We claim:

1. A toy firearm comprising a hollow barrel having a ball receiving recess at its muz-

zle end, an ejector plunger device operable within said barrel and comprising a plunger head, a looped plunger stem having one end 65 secured to said head, and a spring surrounding said stem and abutting against one side of the head carried thereby, a breech block pivoted at one end of said barrel and having a clearance recess, means carried by said breech block within the recess for bringing the plunger into set position, a trigger device for holding the plunger in its set position and also releasing the same, and yielding means for holding said breech block in 75 its normal closed position.

2. A toy firearm including a hollow barrel having a ball receiving recess at its muzzle end, and a spring abutment at the other, a trigger extension at the breech end of the 80 barrel, a spring pressed plunger device operable in said barrel, a breech block hinged to said extension and having a clearance recess, a pin in said recess for engaging the plunger device to set the same, and a trigger device pivotally mounted in said trigger extension 85 and adapted to maintain the plunger device in set position and also release the same.

3. A toy firearm including a hollow barrel having a ball receiving recess at one end and a spring abutment at the other, a trigger extension at the breech end of the barrel, a spring pressed plunger device operable in said barrel and including a slotted stem 95 having a notch, a breech block hinged to said extension and having a clearance recess, a pin in said recess for engaging the stem to set the same, and a trigger device pivotally mounted in said trigger extension and having spring pressed means for engaging the notch in the plunger to maintain the plunger in set position.

4. A toy firearm including a hollow barrel having a ball receiving recess at one end and 105 a spring abutment at the other, a trigger extension at the breech end of the barrel, a spring pressed plunger device operable in said barrel, a breech block hinged to said extension and having a clearance recess, a pin 110 in said recess for engaging the plunger device to set the same, and a trigger device pivotally mounted in said trigger extension and having a vertically movable spring pressed detent for engaging the notch in the 115 plunger.

In testimony whereof we hereunto affix our signatures in the presence of two witnesses.
